SMOKING PIPE

Fred W. Gans, Trenton, N. J., assignor of one-half to Harry A. Mitman, Laurel, Miss.

Application May 26, 1948, Serial No. 29,211

4 Claims. (Cl. 131—183)

1

This invention relates to improvement in tobacco pipes and particularly to improvements in a tobacco pipe such as described and claimed in my United States Patent No. 2,378,400, granted June 19, 1945.

In addition to the objects and advantages obtained in the pipe of my previous patent, it is a further object of this invention to have an ejector type smoking pipe in which a seat is provided for the ejector mechanism. An additional object is to provide an air seal arrangement between the ejector mechanism and the bottom opening in the pipe, said seal arrangement being provided with adjustable means to admit air into the space below the ejector mechanism. Another object is to provide means for locking and unlocking the injector mechanism thus enabling locking together of the operating parts of the pipe, but at the same time enabling quick disassembling of the parts if so desired. Also, another object is to provide a combination of elements which will readily conduct a substantial portion of the heat from the interior of the pipe to the exterior thereof thus obtaining a relative cool smoke. Additional objects of the novel improvements will be obvious through use of the pipe and from the description of the invention.

With the above objects in view, the invention broadly comprises an ejector type smoking pipe, as described in my previous patent, provided with the combination of a tube having a projection on its inner wall, fixed in an opening of the bottom of the pipe, a round plug having a large head and a smaller diameter shank portion for insertion into the tube, said shank of the plug having a circumferential groove for interlocking with the projection of the tube, and the upper edge of the tube adapted to receive a rounded projection formed on the bottom side of the ejector element thus providing a seat for the ejector element and also forming an adjustable air seal in the bottom of the pipe.

In the attached drawing,

Figure 1 shows a side view of an ejector type pipe.

Figure 2 shows a sectional view of an ejector type pipe disclosing the detail of the combination of parts comprising the invention.

Figure 3 is a sectional view on line 3—3, and

Figure 4 is a sectional view on line 4—4 of Figure 2.

Having broadly stated the invention, a more detailed description will now be given with reference to the drawing. In Figure 2 of the drawing a smoking pipe is illustrated with a hollow pipe

bowl 1, an angularly disposed stem 2 with a conventional mouthpiece 3 and a flue 4 extending through the body of the stem and mouthpiece. A guiding channel 5, provided with flanges or retaining edges 6, is inserted in a shallow groove along the lower surface of the pipe stem.

A flat flexible spring 7, provided with a knob 8 near one end and an ejector tobacco and ash supporting plate 10 at the other end thereof, is inserted in the guiding channel 5 and movably held therein by the flanges 6. One end of the guiding channel 5 has a reversely bent edge 9 which is clamped between the mouthpiece 3 and the pipe stem 2 by pushing the mouthpiece firmly into the stem 2; this assists in holding the channel in position. On the under side of the ejector grate 10 is a rounded projection or bead 11, which has a recess 12 into which the end of spring 7 is securely fixed.

20 In the bottom portion of the pipe bowl 1 a hole 13 is provided into which a cylindrical tube or bushing 14, having a teat 15 projecting from the inner wall thereof, is fixed. A round plug 16 having an enlarged circular face or head 17 and a 25 smaller diameter shank portion 18 is inserted into tube 14. The smaller diameter shank portion is provided with a circumferential groove 19 which is adapted to interlock with an internal teat 15 on tube 14, when the shank is inserted therein. The plug 16 is also provided with a slot 20 extending from the top portion through the body portion of the shank 18 of the plug, said slot having its bottom wall curved gradually so as to terminate in the side wall of the enlarged head portion 17 just above the bottom of the plug through the body. It is preferred that the tube 14 and plug 16 be made of metal for purposes hereinafter indicated, although plastic materials may be used if desired.

40 In use the pipe is normally operated as follows: The plate 10 is moved to the lowest position in the pipe bowl by pushing the operating knob 8 toward mouthpiece 3. When the plate is in the lowest position, the rounded projection 11 will be seated on the upper edge of tube 14. While in this position, and the pipe is smoked, air is substantially sealed from the lower portion of the pipe bowl. However, if the smoker chooses to admit air to the lower portion of the bowl to obtain better combustion of the tobacco or possibly a cooler smoke, the knob 8 is merely moved slightly toward the pipe bowl. This action will tend to unseat the rounded projection 11, and some air will be drawn in through tube 14. The air is drawn in through tube 14 by way of slot 20

in plug 16; the slot 20 extends from one end of the plug and opens in the side wall of head 17. Sufficient space exists between guiding channel 5 and spring 7 at the point where spring 7 contacts plug 16, to admit air for the purpose described. Such mixing of air with the smoke functions as a smoke conditioning feature and adds greatly to the smoking enjoyment.

After the tobacco charge in the bowl has been smoked, the ash contents in the bowl are ejected, as described in my previous patent, by moving operating knob 8 toward the bowl thus raising plate 10 toward the upper edge of the bowl and emptying its contents.

As stated in the broad statement of the invention, the novel feature of this invention is in the combination of the rounded projection of the plate, the tube 14 provided with teat 15 and plug 16. Since the upper edge of tube 14 is relatively sharp, it forms a substantially self cleaning seat for the grate. Teat 15, on the inner wall of tube, interlocks with the circumferential groove 19 located on shank 18 of the plug, thus the entire combination of elements are held rigidly in place at all times. For disassembling the pipe elements, engagement between groove 19 and teat 15 may readily be broken as follows: pressure is removed from the reversely bent edge 9 by removing mouthpiece 3, thus the guiding channel 5 including spring 7 move from the plane of the shallow groove along the lower surface of the pipe stem. This movement of the spring is due to the normal tendency of the piece of flexible spring steel to straighten out. As soon as the channel 5 and spring have moved from the shallow groove, plug 16 together with the spring and channel may be turned until slot 20 comes into alignment with teat 15, and the plug and ejecting mechanism are thus free for removal from the remaining parts of the pipe.

In order to more clearly portray the structure of the plug 16 and the interlocking of groove 19 with teat 15, Figure 4 shows an enlarged section view on a horizontal plane through groove 19 of plug 16 and tube 14 in Figure 2; the figure also shows a section through teat 15, which is a part of tube 14, projecting into groove 19 and thus forming a positive locking of the several parts.

Through use of the combination of elements, viz. the plate, tube and plug improved smoking conditions are obtained. A substantially perfect air seal may be obtained but as noted air may readily be admitted, thus combustion of the tobacco charge in the pipe may be controlled entirely by the pipe smoker. Also, through use of the specially designed plate, tube and plug the ejecting mechanism may be locked or unlocked at will without difficulty. By the expression "mechanism may be locked and unlocked," I means the following: "locked" when the mechanism is assembled on the pipe and teat 15 and circumferential groove 19 are engaged to hold plug 16 in tube 14, and "unlocked" when the plug 16 and the ejecting mechanism has been turned, as described to such position so as to be removed from the remaining parts of the pipe. Furthermore, since there is substantial contact between the three metal elements of the combination, heat is readily conducted from the burning tobacco charge to the plate, thence through the tube and tube walls and dissipated to the air by the plug, thus the smoker will enjoy a cooled smoke. The face of the plug is of substantial area so that, amongst other functions, it will enable dissipation of considerable heat to the atmosphere.

Having described the improved ejector pipe, I claim as follows:

1. A smoking pipe comprising a bowl provided with an opening in the bowl bottom, a stem provided with a guiding channel, a tube fixed in the opening of the bowl bottom, a teat projecting from the inner wall of the tube, a movable plate provided with a rounded projection on the bottom side thereof and a flexible element extending from the rounded projection through the tube and into the guiding channel of the stem, a plug provided with a round shank for insertion into the tube, said shank having a groove partially around the shank body and a slot extending from one end of the plug through the body of the shank and curved gradually to open in the side wall of the opposite end of the plug, the teat in the tube being in interlocking relationship with the groove in the shank body, the upper edge of the tube forming a seat for the rounded projection of the plate and the flexible element being received in the shank slot of the plug and guided into the guiding channel of the stem.
2. In combination with a smoking pipe including a bowl provided with an opening in the bottom thereof, a stem provided with a guiding channel and a movable plate provided with a flexible element, the improvement which comprises a tube fixed in the opening in the bowl bottom, a rounded projection on the bottom side of the grate which fixedly receives one end of the flexible element, a plug provided with a round shank for insertion into the tube, said plug having a slot extending from one end of the plug through the body of the shank and gradually curved to open in the side wall of the opposite end of the plug, the upper edge of the tube forming a seat for the rounded projection of the plate and the flexible element being received in the shank slot of the plug and guided into the guiding channel of the stem.
3. In combination with a smoking pipe including a bowl provided with an opening in the bottom thereof, a stem provided with a guiding channel and a movable plate provided with a flexible element, the improvement which comprises a tube fixed in the opening in the bowl bottom, a teat projecting from the inner wall of the tube, a rounded projection on the bottom side of the plate which fixedly receives one end of the flexible element, a plug provided with a round shank for insertion into the tube, said shank having a groove extending partially around the shank body and a slot extending from one end of the plug through the body of the shank and curved gradually to open in the side wall of the opposite end of the plug, the teat in the tube being in interlocking relationship with the groove in the shank body, the upper edge of the tube forming a seat for the rounded projection of the plate and the flexible element being received in the shank slot of the plug and guided into the guiding channel of the stem.

4. A smoking pipe comprising a bowl provided with an opening in the bowl bottom, a stem provided with a guiding channel, a tube fixed in the opening in the bowl bottom, a teat projecting from the inner wall of the tube, a movable plate seated on the upper edge of the tube, a flexible element extending from the plate through the tube and into the guiding channel of the stem, a plug provided with a round shank rotatably mounted in the tube, said shank having a groove partially around the shank body and a slot extending from one end of the plug through the

body of the shank and opening in the side wall of the opposite end of the plug, the slot and seat adapted to come into alignment upon rotatably moving the plug for unlocking the plug from the tube, and the slot and seat adapted to be placed out of alignment from each other to lock the plug with respect to the tube, said flexible element being received in the shank slot of the plug and guided into the guiding channel of the stem when the plug and tube are in a locked position.
